Stuart Weatherley Inventor
By his Attorney Lewis J. Woolittle

UNITED STATES PATENT OFFICE.

STUART WEATHERLEY, OF LONDON, ENGLAND.

BOOT AND SHOE FASTENING.

1,174,641.

Specification of Letters Patent.

Patented Mar. 7, 1916.

Application filed April 13, 1914. Serial No. 831,880.

To all whom it may concern:

Be it known that I, STUART WEATHERLEY, a subject of the King of England, and resident of London, England, have invented 5 certain new and useful Improvements in Boot and Shoe Fastenings, of which the following is a specification.

This invention relates to a fastening device adapted to be used as a boot and shoe 10 fastening, as well as for many other purposes where it is desired to provide a simple and quickly operated means for fastening or holding adjoining edges of two portions of material together.

15 The object of the invention is to provide a simple arrangement and construction for a fastening device of this nature and in carrying out the invention I provide a number of eyelets of peculiar construction which are 20 secured to the adjacent edges of the shoe-top or other material to be fastened. A resilient member is secured to one of these eyelets at one end thereof and at its opposite end is provided with a portion through which a 25 cord or lace may be passed. The opposite eyelet is provided with a portion extending somewhat above the material to which it is secured, which portion is formed so that the 30 said cord or lace may be passed through the same. When the cord or lace is pulled the 35 end of the resilient member is drawn transversely against the opposite eyelet, thus closing and holding the shoe-top, as will be described more fully hereinafter. The resilient member permits a yielding of the shoe-top 40 when closed and thus provides greater flexibility and ease to the wearer.

The above and other features of construction will appear more fully hereinafter in 45 connection with the description of the invention as illustrated in the accompanying drawings.

In the drawings like parts in the several views have been given the same reference 50 numerals.

Figure 1 is a front view of a portion of a shoe-top provided with my improved fastening device, showing the same in its closed position. Fig. 2 is a view similar to Fig. 1, 55 showing the fastening released and in its partly open position. Fig. 3 is an enlarged sectional view through one of the fastening eyelets. Fig. 4 is an enlarged sectional view 60 through the opposite eyelet.

The two sections of a shoe-top are shown 55 at 1 and 2, respectively, to which the eyelets 3 and 4 are secured.

A resilient member 5, which may be in the form of a coil spring flattened transversely, 60 is secured to the eyelet 4 by engaging one end thereof beneath the inwardly projecting portions 6 and 7, as shown in Fig. 4.

The projections 6 and 7 may be conveniently formed by punching out strips 65 from the eyelet 4 and bending the same upwardly and inwardly to meet at the center, as shown in Fig. 4, the last coil on one end of the resilient member 5 being engaged beneath these inwardly projecting members.

The eyelet 3 is provided with an upwardly 70 extending loop 8, which may be conveniently formed by bending a wire ring at right angles and engaging one portion of the ring beneath the bent-over portions of the eyelet. The other portion of the ring will then 75 extend upwardly in the form shown in Fig. 3 and forms an opening through which the cord or lace 9 is passed.

The outer or extending end of the resilient member 5 is provided with an opening 80 through which the cord or lace 9 is passed. This may be conveniently formed by bending the end loop of the resilient member 5 at an angle with the remaining coils, as 85 shown at 10.

The cord 9 is passed alternately through the successive openings provided by the loop 8 in the eyelet 3 and the loop or ring 10 at the end of the resilient member 5, the cord 90 being secured at its lower end by any suitable means. When the cord is pulled from its upper end the fastenings and the two sections of the shoe-top are brought together from the position shown in Fig. 2 to that shown in Fig. 1 and are held in this 95 closed position by tying or otherwise securing the cord at its upper end. When it is desired to loosen or open the shoe-top the cord is pulled down from an intermediate point, thus loosening the same to permit the 100 fastenings to be separated and opened. When the shoe-top is secured together the resilient members 5 permit a slight yielding of the same and thus impart a flexibility to the shoe which it is not possible to obtain 105 with a rigid fastening.

It will be noted that the device is extremely simple in construction and opera-

tion, may be cheaply manufactured and presents a neat appearance, as will be obvious.

I do not wish to be understood in limiting my invention in any sense to the particular form shown and described or to any particular material which may be used in its construction and, while the invention is intended primarily as a boot and shoe fastening, it will be obvious that the same readily lends itself to various other uses. The drawings and description herein are intended as illustrative merely of the invention as defined in the accompanying claims and not in a limiting sense.

What I claim is:

1. A fastening device comprising a resilient member secured to one edge of the material to be fastened, means associated 20 with the opposite edge and permanently connected to the resilient member, said means adapted to draw upon the resilient member thereby pulling the edges together.
2. A fastening device of the class described, comprising a plurality of resilient members secured to one edge of the material to be fastened, eyelets secured to the opposite edge, a member connected to the resilient members and adapted to pass 30 through the eyelets constituting a means for tensioning the resilient members thereby drawing the edges together.
3. A fastening device of the character de-

scribed, comprising a plurality of resilient members secured to one edge of the goods, 35 eyelets secured to the opposite edge, and a flexible element operatively associated with the resilient members and eyelets for placing the resilient members under tension thereby drawing the edges together. 40

4. A fastening device of the class described, comprising a resilient member detachably secured to one edge of the material to be fastened, and a member carried by the opposite edge and connected to the 45 resilient member constituting a means for tensioning the resilient members thereby drawing the edges together.

5. A fastening device of the character described, comprising a plurality of spring 50 members detachably secured to one edge of the goods to be fastened, said members provided at their free ends with loops, a plurality of eyelets arranged on the opposite edge of the goods, and a flexible member 55 adapted to be alternately laced through the loops and eyelets thereby constituting a means for tensioning the spring members and pulling the edges together.

Signed at the city, county and State of 60 New York, this 10th day of April, 1914.

STUART WEATHERLEY.
